UNITED STATES PATENT OFFICE.

A. ZELIFF WILLIAMS, OF CHICAGO, OHIO.

BRICK OR TILE CUTTER.

SPECIFICATION forming part of Letters Patent No. 488,343, dated December 20, 1892.

Application filed October 12, 1891. Serial No. 408,504. (No model.)

To all whom it may concern:

Be it known that I, A. ZELIFF WILLIAMS, a citizen of the United States, residing at Chicago, in the county of Huron and State of Ohio, have invented a new and useful Brick-Cutting Machine, of which the following is a specification.

This invention relates to a machine for cutting brick; and the objects in view are to provide a cheap and simple machine of this class, adapted to be run with small expense and to be operated in part by the passage of the clay from the die of the brick-machine, whereby said machine may be said to be automatic in its operation, to adapt the machine for delivering the brick as cut, to be afterward manipulated for the purpose of drying; and to adapt the machine for cutting the brick cleanly and with accuracy.

Various other objects and advantages of the invention will appear in the following description, and the novel features thereof will be particularly pointed out in the claims.

Referring to the drawings:—Figure 1 is a side elevation of a brick machine constructed in accordance with my invention. Fig. 2 is a plan of the same. Fig. 3 is a longitudinal section. Fig. 4 is a transverse section, on the line 4—4 of Fig. 1. Fig. 5 is a horizontal section on the line 5—5 of Fig. 1. Fig. 6 is a transverse section on the line 6—6 of Fig. 3. Fig. 7 is a transverse section on the line 7—7 of Fig. 3. Fig. 8 is a longitudinal section, on the line 8—8 of Fig. 5. Fig. 9 is a detail in transverse section on the line 9—9 of Fig. 2. Fig. 10 is a detail in longitudinal section on the line 10—10 of Fig. 5.

Like numerals of reference indicate like parts in all the figures of the drawings.

In this instance, upon the oblong base or support 1 there are bolted the four supporting-legs 2 of an oblong frame 3; which frame is provided upon its inner side and at its ends with pairs of opposite short tracks or ways 4, the ends of which are upwardly-disposed, forming stops.

Supported upon axles 5, Figs. 3 and 8 provided at their ends with flanged wheels 6, designed to ride upon the tracks 4, is an open framework or carriage 7, comprising in its make-up side, bottom, and top-walls. (See Figs. 3 and 8.)

A small framework or support 8, is supported upon the base 1, near one end of the machine; and upon the same bearing-boxes 9 55 are located, which boxes have mounted for rotation therein a short shaft 10, the outer end of which is operated by a rag-wheel 11, to which motion is conveyed from a brick-machine or engine for operating the same, 60 through any suitable intermediate set of gearing.

From a cross-bar 13, Figs. 3, 5, and 6 connecting the opposite side-bars of the frame 3, rise standards 14 and 15, the same being located at opposite sides of the frame, and therefore at the longitudinal ends of the bar 13. That standard 14 is provided with a vertical slot 16, while to the opposite standard there is pivoted as at 17, a transversely-disposed bar 18, the free end of which is designed to move in the vertical slot of the standard 14. This bar is provided at its center with a bearing 19, Fig. 3 and in the same is journaled one end of a section 20 of the shaft 75 10, the outer end of the section 20 being connected to the section 10, by a gimbal-joint 21.

Upon the shaft 20 within the frame 7 there is mounted a basket-pinion 22, of considerable length.

Pairs of standards 24 Figs. 1 and 4 having a general L-shape, are secured to the opposite sides of the frame 7, near one end of the same, and each pair is connected by a transversely-disposed reciprocating-rod 25. These 85 rods are mounted in bearings 26, formed in the upper ends of the standards 24, and in the present instance are cylindrical in cross section, though they may be in any shape desired; and in length are about twice as long 90 as the distance between each transversely opposite pair of standards in which they are mounted. The ends of the rods outside of the standards are connected by cross-heads 27, from the centers of which depend arms 28, 95 said arms extending down the opposite sides of the frame 7, and are connected by upper and lower rack-bars 29 and 30 respectively, that extend transversely through the frame 7. These rack-bars are arranged at opposite 100 sides of the basket-pinion 22, and have their teeth formed upon their inner sides so that each bar may be engaged by the pinion by an alternate raising and lowering of the lat-

ter (see Fig. 4.) At their opposite ends the rack-bars are provided with plain untoothed portions 32, which when occupied by the basket pinion, permit of the latter running idly 5 and without operating the rack-bar. The lower rack-bar is provided upon its front face with a series of teeth 33, Fig. 5 which engage and operate a gear-wheel 34, journaled as at 35, in the front end of the framework 7, upon 10 a suitable cross-bar 36.

A tray 37 is secured in the front end of the frame 7, and in the same there is mounted for loose rotation a series of rollers 38, the faces of which are preferably covered by some textile or other material. In rear of the rollers there is secured to the opposite sides of the frame a series of cross-strips 39, Figs. 3, 4, and 7, which are bolted in position by bolts 40, and are located a slight distance apart. 15 Any number of these cross-strips may be employed, in accordance with the number of brick that are to be cut simultaneously. Bolted to the cross-strips by the bolts 40 are pairs of opposite L-shaped standards 41, rising 20 a short distance above the cross-strips. These standards are flanged at their upper ends, as shown, and are slotted at their lower ends, whereby they may be adjusted at proper distances apart. Each pair of standards is 25 connected by an upper cross-piece 42, slotted near their ends as at 43, and adjustable upon the upper flanged ends of the standards through the medium of bolts 44. The upper cross-strips 42, the standards 41, and the lower cross-strips 39, are all alike arranged in groups or spaced from each other by narrow intervening spaces 45. (See Fig. 3.)

Sleeves 46 Fig. 2 are mounted upon each of the rods 25, and are designed to move with 40 the rods. The sleeves are preferably adjustable, and are provided upon their upper sides with movable boxes 47, in which is journaled for rotation a transverse shaft 48. A series of in this instance three circular thin steel 45 knives 49 are mounted upon the shaft 48 and by means of collars 50 are spaced apart so as to register with the narrow spaces 45 existing between the upper and lower cross-bars 42 and 39, and the standards 41; so that as the 50 rods 25 reciprocate, the cutters pass between the said upper and lower cross-strips and standards, and the latter containing a cake of clay serve as so many molds in which the series of bricks are formed by the passage of the cutters. The upper peripheries of the loose rolls 38 are about in the same plane with the lower cross-strips 39, and located between the rear roll of the series and the front cross-strip is a chute or reduced passage 51, Fig. 2 55 60 the opposite side-walls of which are inclined so that the clay is guided in a proper form into the brick-forming frames.

In rear of the pairs of standards 24, a pair of opposite parallel ways 52 are mounted upon 65 the upper side of the frame 7; and outside of the ways a pair of transversely opposite standards 52 are located, said latter standards be-

ing slotted as at 53 Fig. 1 for the reception of bolts 54 by which the standards are longitudinally adjustable upon the frame 7.

In bearing-openings 55 Fig. 9 formed in the upper ends of the standards 52, a transverse shaft 56 is loosely mounted. This shaft is provided adjacent to one of the standards with a ratchet 57, Figs. 2 and 9 rigidly mounted upon the shaft, and a collar some distance from the ratchet also rigidly mounted upon the shaft.

Between the ratchet and collar a gear-wheel 58 is loosely mounted on the shaft, and at one side of the gear-wheel a disk 59 is likewise loosely mounted, but made rigid with the gear-wheel. A pawl 60 is pivoted to the disk and a spring 61 also secured to the disk serves as a means for pressing the operating end of the pawl yieldingly into engagement with the teeth of the ratchet-wheel. Near its center the shaft carries a radial rigid wing 62, Figs. 2 and 3 and at that end of the shaft opposite which the just previously described mechanism is located, and outside of its bearing, there is secured a weighted crank-arm 63, Figs. 1 and 2 upon which a weight 64 is adjustably mounted, and also a shoulder 65, the latter being designed to engage and interlock 95 with a spring-catch 66 slotted and made adjustable by means of a bolt 67 which serves as an attaching means to the adjacent standard 52. At the inner side of the standard 52 just mentioned, an arm 68 Fig. 2 is located, and adapted to revolve with the shaft 56, said arm having its free end beveled, whereby it is adapted to engage with the notched end 69 of a lever or catch 70, Fig. 3 pivoted as at 71 to the inner side of the said standard 52.

In bearing-brackets 73, extending rearwardly from the rear pair of standards 24, a rock-shaft 74 is mounted, and the same is provided with a pair of forwardly-disposed pins 75 and 76, located near the right and left-hand ends respectively of the said rock-shaft, and in the path of the opposite beveled faces of a trip-lug 77, depending from the inner bearing-sleeve 46. A rock-arm 78 Fig. 3 also extends from the shaft 74, though disposed rearwardly, and its free end is loosely connected by a link 79 to the free or front end of the catch-lug 70, the ends of the link being pivoted to the rock-arm 78 and catch-lever 70, as indicated at 80. A coiled spring 81 is connected to the rock-arm 78 near its free end, the opposite end of said spring being connected to the sides of the frame 7. By means of this spring 81 the pins 75 and 76 are normally maintained in the path of the trip-lug 77, and the rear or shouldered end of the catch lever 70 is maintained elevated in the path of the free end of the arm 68. Mounted for movement in the ways 52 is a table 82, the same being provided at one side with a pair of standards 83, Figs. 4 and 9 longitudinally opposite each other and supporting a rack-bar 84, the teeth of which are upon the upper side of the bar, engage with

and operate the gear-wheel of the transverse shaft 56, such operation taking place by reason of the movement of the table 82, caused as will be hereinafter described (see Figs. 1 to 4.)

5 A pair of side-bars 85 extend rearwardly from the frame 7 and from between the ways, and have their upper edges slightly below the ways, whereby the delivery table 82 may be reciprocated thereover, for a portion of its 10 movement. In the side-bars is journaled a series of loose rollers 86, and over the same an endless apron 87 passes.

A shaft 88, Figs. 5 and 10, passes transversely through and is journaled in the frame 3, in rear of the slotted standard 14, the inner 15 end of the shaft being supported by a bar 89 of the frame 3; and between the outer side of the frame and the bar 89 there is mounted upon the shaft a ratchet-wheel 90, which wheel 20 is fast upon the shaft. At one side of the ratchet-wheel a disk 91 is loosely mounted upon the shaft, said disk being provided upon its outer side with a gear-wheel 92 likewise loose upon the shaft but fast upon the disk.

25 Upon the opposite side of the disk a pawl 93 is pivoted, and by a spring 94 the free end of the pawl is maintained in operative engagement with the teeth of the ratchet-wheel 90. Outside of the frame 3 a gear-wheel 94^a is 30 mounted upon the shaft, and also a disk 95. In front of the disk there is pivoted to a bracket 96, as at 97, a head 98, from which extends rearwardly a pair of rods 99, the rear ends of the rods being connected by a head 35 100, having a central perforation. A plunger-rod 101 is connected by a wrist-pin 102 to the outer face of the disk 95, passes through the perforation in the head 100, and is connected to the center of a head 103, provided 40 near its ends with perforations for the reception of the rods 99 upon which the head 103 is adapted to reciprocate. A coiled spring 104 is mounted upon the plunger-rod 101 and is interposed between the heads 100 and 103. 45 These parts constitute a yielding extensible pitman, and as a spring connection for aiding in the rotation of the disk 95 and consequently the shaft 88. (See Figs. 1 to 5.)

In the side of the frame and the bar 89, immediately in front of the shaft 88, a second transverse shaft 105 Fig. 5 is journaled, and upon the outer end of the shaft a gear 106 is located, said gear engaging with the gear 94^a of the shaft 88. Upon the inner end of the 55 shaft 105 a disk 107 is mounted, and the same by a wrist-pin 108 is connected by a pitman 109 to an L-shaped pin 110, projecting from the vibrating lever or arm 18.

From the opposite sides and the bottom of the table 82 depend brackets 111, and in the same are pivoted depending arms 112, the same being connected at their lower ends by a cross-bar or rod 113 Fig. 3. Depending 60 from the center of the rod 113 and rigid therewith, is a lever 114, to the lower end of which is pivoted, by a bolt 115, adjustable in any one of the holes in the lower end of the lever,

a fulcrum-bar 116, the front end of which is pivoted as at 117, to a depending standard 118, the upper end of which is secured to the 70 underside of the cross-bar 30 of the frame 7.

A coiled-spring 119 has its rear end connected to the bolt 115, and its front end to an adjusting-rod 120, the front end of which is threaded and projects through an opening 121 formed 75 in the front end of the frame 2 and is there provided with a nut 122. By manipulating the nut upon the rod the tension of the spring may be regulated or decreased, as may be desired. To a wrist-pin 123, projecting from 80 the under-side or face of the gear-wheel 34 is pivoted the front end of a pitman 124, the rear end of which is flexibly and pivotally connected to a bolt 125 by means of a pair of straps 126, perforated and engaging pins 127, 85 which extend from the opposite side of a cylindrical block 128, pivotally mounted on the bolt. This completes the construction, with the exception of a series of keepers 129, Fig. 4 which are secured to the sides of the frame 90 7, and depend under and loosely engage with the longitudinal side-bars of the supporting-frame 3.

This being the construction, the operation is as follows:—The tray 37 containing the rollers 38 is filled with water or oil, which is absorbed by the surfaces of the rollers which become thus coated and slightly non-adhesive. The machine being set in motion, the clay is conducted from the die of the brick machine 95 100 in a long blank, is forced by the machine over the rollers through the chute at the front end of the machine, and into the brick-frames between which the rotary knives are to run. When this has been accomplished, the frame 105 7 is pushed to the rear by hand, so as to ride upon the loose wheels and the tracks 6 and 4 respectively. Such movement of the frame through the medium of a rack-bar 130, causes a rotation of the gear 92, the disk 94, and the 110 ratchet-wheel 90, the latter through the medium of the pawl of the disk that is engaged with the ratchet-wheel. Such movement upon the part of the shaft 88 rotates the disk 95 one half against the tension of the 115 spring 104 of the pitman, and the remaining half or return of the pitman is caused by the tensile force of said spring. Hence the object of employing the extensible pitman is to obviate the necessity of moving the 120 frame 7 too long a distance. The rotation of the shaft 88 is imparted to the gear 106, and the latter rotates the shaft 105, the disk 107 and through the medium of the connecting-rod 109, vibrating the bar 18 in one 125 direction. Such vibrations of the rod serve to shift or throw the basket-gear into operative engagement with either the teeth of the upper or lower rack-bars 29 or 30 in accordance with the movement given the shaft 20, 130 and such movement is permissible upon the part of said shaft by reason of the gimbal-joint between the sections 10 and 20 thereof.

When the basket-gear is thrown into such en-

gagement and is rotated by its shaft, which as before stated is in operative connection with a suitable motor, as the engine that runs the brick - machine, or the brick - machine itself, it serves to reciprocate transversely the cutter - carrying frame the cutters passing through the lump of clay contained within the brick frames and cutting the same into bricks. The first reciprocation of the machine is preferably made by hand, as before stated; but whether it is reciprocated by hand or means hereinafter described, the large coiled spring 119 serves to retract the frame. The bricks having been cut and the incoming clay pressing against the rear end brick of the series forces said series to the rear against the delivery-table 82, and pressing against the wing 62, located above the table, serves to reciprocate the frame 7, and in the manner heretofore described shift the basket-gear, which has in the meantime been running idly, into engagement with the opposite rack-bar; so that the cutters traverse in the opposite direction, making the second cut. As the cutters begin to traverse, the trip-lug 77 has come into contact with the adjacent pin 75 or 76 whichever it may be, and thus the shaft 74 is rocked against the tension of the spring 81 and through the medium of the link 79 the rear end of the catch-lever is elevated so as to liberate the arm 68, and the wing 62. At this point the weight 64 dropping to a vertical position elevates the wing slightly and the delivery-table 82 makes its rearward movement, its rack-bar 84 serving to entirely rotate the shaft 56 and the wing 62, and throw the parts into locked position behind the bricks on the table 82. By the return of table 82 the bricks being on the rear side of the locked wing 62, are deposited upon the endless belt 87, and in its return rotates the gear 58 of the shaft 56 but the latter being loose on said shaft and only operating with it in one direction, does not influence the shaft, its pawl 60 riding lightly over the ratchet wheel 57. The cutters having now passed out of the lump of clay, the freshly cut bricks are forced on the table 82, partly by the return of frame 7 caused by the tension of spring 119, and partly by the oncoming blank of clay. The rearward reciprocation and return of the delivery table is accomplished through the medium of the pitman 124, which is operated by the revolutions of the gear-wheel 34, and it in turn is operated by the side teeth of the lower rack-bar 30. It will be understood that these mechanisms are properly timed so as to combine and relatively operate at proper steps of the operation of the machine, and it will also be observed that for the purpose of facilitating such proper timing most of the parts are made adjustable.

From the foregoing description, taken in connection with the accompanying drawings, it will be seen that I have provided a machine of simple construction, that is adapted to suc-

cessively, accurately and rapidly cut series of bricks, the action of the machine leaving no rough edges or other objectionable features to indicate that the brick has thus been manufactured. It will be seen that the machine is entirely automatic in its operation, in that the cutting of one set of brick and their forward movement serves to throw the mechanism into operative connection in a reverse manner, and thus repeat the cutting, and so on. After the delivery of the brick the basket occupies the untoothed spaces of the rack-bars, and runs idly; so that no unnecessary wear of the mechanism takes place. The brick after formation may be taken from the endless belt and placed upon trucks to be run into kilns for the purpose of burning, or if preferred the endless belt may extend into suitable drying-chambers through which the brick may be conducted.

I do not limit my invention to the exact details of construction herein shown and described, as many changes not seriously affecting the construction thereof will no doubt suggest themselves; and I therefore deem such variations of details as within the scope of my invention.

Having described my invention, what I claim is:—

1. In a machine of the class described, the combination with a frame, a series of brick-receiving frames mounted thereon and spaces between the same, of transverse guide-rods thereabove, rotatable cutting-disks mounted in the spaces and upon the guide-rods, and means for reciprocating the disks, substantially as specified.

2. In a machine of the class described, the combination with a frame, a series of brick-receiving frames spaced apart and mounted thereon, of a series of cutting disks one for each space, a shaft for supporting the disks, bearings mounted at opposite sides of the frames, rods connected at their ends and mounted for reciprocation in the bearings, boxes secured to the rods and receiving the disk-carrying shaft, and means for reciprocating the rods, substantially as specified.

3. In a machine of the class described, the combination with the frame, a series of brick-frames having intervening spaces, of opposite pairs of bearing-standards having openings, rods mounted loosely in the openings and adapted to reciprocate, heads connecting the rods, standards depending from the heads, an upper and a lower toothed rack-bar connecting the standards below the rods, a shaft located between the rack-bars, a gear of a less diameter than the distance between the rack-bars, means for rotating the gear, a shaft connecting the rods and a series of disks agreeing with and opposite the spaces between the frames mounted on the shaft, substantially as specified.

4. In a machine of the class described, the combination with the frame, of the series of adjustable brick - frames spaced apart and

mounted on the frame, the cutters mounted for movement between the brick-frames and means for reciprocating the cutters, substantially as specified.

5 5. The combination with the frame, the series of lower transverse strips spaced apart and mounted on the frame the series of slotted L-shaped standards flanged at their upper ends, and mounted at opposite ends of the cross-strip, the series of upper cross-strips provided with slots and adjusting-bolts passed through the slots of the upper cross-strips and the standards, of the series of cutters mounted for reciprocation between the frames thus 15 formed and means for reciprocating the cutters, substantially as specified.

6. In a machine of the class described, the combination with the frame, a series of brick-frames mounted thereon, and spaced apart, 20 of pairs of standards located at opposite sides of the frames, cutter-carrying rods mounted for reciprocation in the standards, heads connecting the rods, standards depending from the heads, toothed rack-bars connecting the 25 lower ends of the standards and provided at diagonally opposite ends with untoothed portions, a bearing standard located at one side of the framework, a sectional shaft journaled therein and having its sections connected by 30 a gimbal-joint, a gear mounted on the inner end of the shaft and of a lesser diameter than the distance between the rack-bars, and means for raising and lowering the inner section of the shaft when the rack-bar's untoothed 35 face arrives opposite the gear, substantially as specified.

7. In a machine of the class described, the combination with the lower framework, and the upper reciprocating frame, of a stop mounted 40 upon the movable frame, cutting mechanism arranged in advance of the stop, mechanism for operating said cutting mechanism, and devices operated by the reciprocation of the frame as caused by the arrival of clay 45 against the stop, for operating or throwing into gear said cutter-operating mechanism, substantially as specified.

8. In a machine of the class described, the combination with the lower frame, and the reciprocating frame mounted thereon, of a 50 stop mounted upon the reciprocating frame and adapted through the medium of the incoming blade to reciprocate the movable frame, brick-frames mounted in advance of 55 the stop, standards located at opposite sides of the brick-frames, rods mounted for reciprocation in the standards, a shaft and heads connecting the rod, the disks mounted upon the shaft for reciprocation between the frames 60 upper and lower rack-bars connecting the upper and lower ends of the standards, a loosely-hung power-shaft, a gear mounted on the same, and of lesser diameter than the distance between the rack-bars, and mechanism oper- 65 ated by the movements of the frame as caused by the force brought to bear against the stop, for raising and lowering said gear into and

out of engagement with the said rack-bars, substantially as specified.

9. In a machine of the class described, the combination with the lower frame of the upper reciprocating frame, cutting mechanism, upper and lower rack-bars connected therewith for moving said mechanism, a shaft located between the rack-bars, a gear of a lesser 75 diameter than the distance between the rack-bars mounted on the shaft, a pivoted bearing-bar for supporting the rear end of the shaft, a lower transverse shaft, a pitman on the inner end of the same, and devices between the movable frame and transverse shaft, for rotating said shaft and raising and lowering the bearing-bar, substantially as specified. 80

10. In a machine of the class described, the combination with the frame, the reciprocating upper frame mounted thereon, the cutting mechanism, the upper and lower rack-bars for operating the same, the loosely-hung shaft between the rack-bars, the gear mounted on the shaft for engaging with the rack-bars, 90 and of a lesser diameter than the width between the same, a pivoted bearing-bar for the reception of the rear end of the gear-supporting shaft, a lower transverse shaft, a disk on one end of the same and a gear 95 on the other, a pitman connecting the disk with the bearing-bar, a rear transverse-shaft, a fast and loose gear mounted thereon, the fast gear engaging with the gear before mentioned of the transverse shaft, a ratchet located at one side of the loose gear, a pawl upon the loose gear, spring-pressed into engagement with the ratchet, a rack-bar on the movable frame engaging the teeth of the loose gear, an extensible spring-pitman connecting to the lower stationary frame a disk mounted on the rear transverse shaft and connected by a wrist-pin to the pitman, and means for pushing the reciprocating frame to the rear, substantially as specified. 100

11. In a machine of the class described, the combination with the lower frame and the upper stationary frame having a rack-bar, of a transverse shaft mounted in the lower frame, a loose gear mounted thereon, a ratchet 115 wheel at one side of the gear, a pawl spring-pressed into engagement with the ratchet-wheel and fixedly connected with the loose gear, a disk on the outer end of the shaft, a 120 bracket extending from the lower frame, a 120 head pivoted on the bracket, rods extending from the head, a perforated head connecting the ends of the rod, a perforated head mounted for reciprocation on the rods, a pitman pivoted to the disk and passed through the 125 rear perforated head and connected to the reciprocating-head, a coiled-spring interposed between the two heads and mounted on the pitman, and means for reciprocating the frame in one direction, substantially as specified. 130

12. In a machine of the class described, the combination with the frame, and brick-cutting mechanism, together with means for op-

erating the latter, of a reciprocating delivery-table located in rear of the cutting mechanism, means for locking the table against reciprocation, and devices between the cutting mechanism and the table for liberating the same, substantially as specified.

13. The combination with the lower frame, of the upper movable frame having ways, a delivery platform mounted on the ways and 10 designed to reciprocate, cutting mechanism located in front of the ways and platform, standards located at opposite sides of the ways, a shaft mounted for rotation in the standards and provided with a central 15 pending ring, and with a depending arm, a pivoted catch-lever for engaging said arm, a spring for normally elevating the front end of the catch-lever in the path of the arm, and means intermediate the cutting mechanism 20 and operated thereby for elevating said rear end of the catch-lever and liberating the arm, substantially as specified.

14. In a machine of the class described, the combination with the lower main stationary 25 frame provided with tracks, rollers mounted thereon, and a reciprocating-frame mounted upon the rollers; of opposite pairs of standards secured to the opposite sides of the reciprocating frame, a pair of rods mounted for 30 transverse reciprocation in the standards, boxes fixedly mounted upon the rods, a cutter-carrying shaft journaled in the boxes, a bevel-faced trip lug mounted on the rear box, brackets extending from the rear standards, 35 a rock-shaft journaled in the brackets and having near its opposite ends forwardly-disposed pins arranged in the path of the lug, and a rearwardly-disposed arm, a reciprocating mechanism for operating the rods and 40 cutter shaft, a pair of standards arranged in rear of the rock-shaft, a shaft journaled in standards and carrying a depending wing 45 adapted to serve as a stop, a lever depending from the shaft, a catch-lever located below the same and adapted to engage the free end of said lever, a link connecting the rear end of the rock-arm with the front end of the catch-lever, a spring for depressing the arm, and means for throwing the cutter-shaft operating mechanism into operation, said means 50

being operated by the movement of the upper frame substantially as specified.

15. In a machine of the class described, the combination with the stationary frame, of a superimposed movable frame having tracks, 55 a delivery-table mounted for reciprocation in the tracks and provided at one side with a rack-bar, standards secured to the movable frame at the sides of the delivery-table, a shaft journaled in the standards, a ratchet-wheel rigidly mounted on the shaft, a gear loosely mounted on the shaft at one side of the ratchet, engaged by the rack-bar of the table and carrying a spring-pressed pawl for engaging the ratchet-wheel, a wing depending from the center of the shaft over the table, a cutting mechanism arranged in front of the table, mechanism for operating the cutting mechanism, which operating mechanism is set in motion by the movements of 70 the movable frame, locking-devices for the wing carrying shaft whereby the same is made rigid with the movable frame, and devices operated by the cutting mechanism for liberating the said locking-devices and wing-carrying shaft, substantially as specified. 75

16. In a machine of the class described, the combination with the movable frame having ways, a delivery-table mounted in the ways, opposite standards located at the sides of the 80 frame, a wing-carrying shaft journaled in the standards, mechanism between the table and shaft for operating the latter by the movements of the table, of locking-devices for the shaft, a cutting mechanism arranged in front 85 of the table, devices between the cutting mechanism and locking mechanism whereby the latter is operated by the former, an arm extending from the shaft at an angle to the wing and carrying a weight, and a spring-catch for engaging the arm, substantially as 90 specified.

In testimony that I claim the foregoing as my own I have hereunto affixed my signature in the presence of two witnesses.

A. ZELIFF WILLIAMS.

Witnesses:

J. A. PITTSFORD,
OSCAR M. WILLIAMS.
